UNITED STATES PATENT OFFICE.

EMORY P. SEIDEL, OF RIVER FOREST, ILLINOIS.

DESIGN FOR A RADIATOR CAP.

Application filed June 5, 1926. Serial No. 17,949. Term of patent 14 years.

To all whom it may concern:

Be it known that I, EMORY P. SEIDEL, a citizen of the United States, and a resident of River Forest, Cook County, Illinois, have invented a new, original, and ornamental Design for Radiator Cap, of which the following is a specification, reference being had to the accompanying drawing, forming part hereof, in which—

Fig. 1 is a top plan, and Fig. 2 is a side elevation.

I claim:

The ornamental design for a radiator cap, substantially as shown.

In testimony whereof, I have signed my name to this specification this 28th day of May, 1926.

EMORY P. SEIDEL.
